UNITED STATES PATENT OFFICE.

PAUL PIGNOT, OF YONKERS, NEW YORK, ASSIGNOR TO ALEXANDER SMITH & SONS CARPET COMPANY, OF SAME PLACE.

DESIGN FOR A CARPET.

SPECIFICATION forming part of Design No. 14,029, dated July 3, 1883.

Application filed May 4, 1883. Term of patent 3½ years.

To all whom it may concern:

Be it known that I, PAUL PIGNOT, of Yonkers, Westchester county, New York, have invented a new and original Design for Carpets, 5 of which the following is a specification.

The accompanying photograph illustrates my new design for carpets.

This invention relates to a new design for carpets, oil-cloths, and analogous fabrics; and 10 it consists of the new ornamentation of parts hereinafter more fully pointed out.

The letter A in the accompanying photograph represents a bouquet of many flowers turning out from a central group in sprays that extend in all directions, embracing also a 15 lighter shrub-like structure, a, that extends likewise from said bouquet, as shown.

I do not claim anything shown in Design Letters Patent No. 13,705, of March 6, 1883.

I claim—

The design for carpets, consisting of the floral group A, having extension a, substantially as shown.

PAUL PIGNOT.
